UNITED STATES PATENT OFFICE

CLARENCE R. ECKERT, OF ENGLEWOOD, NEW JERSEY, ASSIGNOR TO THE BARRETT COMPANY, OF NEW YORK, N. Y., A CORPORATION OF NEW JERSEY

DESIGN FOR A SHINGLE ROOF

Application filed December 31, 1930. Serial No. 38,164. Term of patent 14 years.

To all whom it may concern:

Be it known that I, CLARENCE R. ECKERT, a citizen of the United States, residing at Englewood, in the county of Bergen and State of New Jersey, have invented a new, original, and ornamental Design for Shingle Roof, of which the following is a specification, reference being had to the accompanying drawing, forming part thereof.

Fig. 1 shows a detail of the element used in producing the design for the shingle roof illustrated in Fig. 2; and,

Fig. 2 is a plan view of a section of the shingle roof of the new design.

The dominant feature of the present invention resides in a roof made up of like shingle elements, shown in Fig. 1, laid in courses as depicted in Fig. 2, each course having exposed along one longitudinal edge spaced semi-hexagonal tabs, the length of the forward edges of the tabs being substantially

equal and equal to the length of the inner edges of the spaces between the tabs, each course having two contiguous like tabs, the side edges of which are of unequal length, alternating with a third tab having the side edges of equal length, the forward edges of the tabs of the shingles of one course substantially coinciding with the inner edges of the recess of the shingles of an underlying course, thus forming rows of geometrical hexagonal figures inclined to the eaves, two rows of figures all of which are of like size and shape and of distorted hexagonal appearance alternating with one row of figures all of which are of like size and shape and of regular hexagonal appearance.

I claim:

The ornamental design for a shingle roof substantially as shown and described.

CLARENCE R. ECKERT.
